RECORDING APPARATUS

Henry L. Tholstrup, Rochester, N. Y., assignor to
 International Business Machines Corporation,
 New York, N. Y., a corporation of New York

Application December 14, 1944, Serial No. 568,161

1 Claim. (Cl. 164—113)

This invention relates to recording apparatus and more particularly to improvements in code recording apparatus of the type wherein a plurality of code punches corresponding, respectively, to the code positions of a predetermined code system are selectively operated by cyclic means to punch a code hole or holes in a field of a record strip representing different data in accordance with such code system. The present application is a continuation in part of my copending application Serial No. 492,895, filed June 30, 1943.

The invention has for a general object to provide apparatus of the type explained which is of new and improved construction and which operates in an effective manner.

A further and more specific object is to provide apparatus of the type referred to, including a new and improved key operated means which, when actuated, provides for the selective operation of the code punches during one operating cycle and prevents a repeat operation of such code punches until the key operated means has first been manually released.

Other objects of the invention will be pointed out in the following description and claim and illustrated in the accompanying drawings, which disclose, by way of example, the principle of the invention and the best mode, which has been contemplated, of applying that principle.

In the drawings:

Fig. 1 is an isometric view illustrating somewhat diagrammatically the structure of the code tape punch shown in my copending application, referred to above, certain elements having been added for the purposes of the present disclosure; and

Fig. 2 is an electrical wiring diagram illustrating the component electrical elements and their circuit connections, which form parts of the preferred embodiment of the present invention.

Referring now in detail to the construction illustrated, it is noted that the code tape punch shown in Fig. 1 is identically the same as is shown in detail in Figs. 7 to 16 inclusive of the above identified copending application of which this application is a continuation in part, with the exception that a cam 7 and a pair of contacts 8 operated thereby have been added to the construction of Fig. 1 hereof. My aforementioned copending application contains a full and detailed description of the structure and operation of the tape punch. Only a general description of the main parts of this apparatus and their operation is required herein for a full understanding of the present invention.

The tape punch is indicated generally by the reference character 10 and comprises six code punches indicated, respectively, by the reference characters RP1 to RP6 inclusive, and one feed hole punch FP. The code punches RP1 to RP6 correspond, respectively, to the six code positions of a predetermined combinational hole code and are so arranged that when selectively operated in a manner which will be presently explained, each will punch a code hole in a corresponding code position of a recording field in a record tape 11. The code punches are arranged in a vertical line as shown and the tape is advanced in steps by a feed wheel 12 to bring successively blank recording fields into position where they can be punched. The six code positions in the tape 11 are indicated at the left-hand end thereof by the numerals 1 to 6 inclusive. If desired, the same code system may be used herein as is disclosed in Fig. 18 of my copending application, referred to above. It is noted that the feed hole punch FP is positioned between code punches RP2 and RP3 and will operate during each cycle of operation to punch a small feed hole 13 in the tape between code positions 2 and 3. The radial pins 14 of the feed wheel 12 engage the feed holes to advance the tape, as will be readily understood.

As disclosed in my copending application, the code punches and the feed hole punch are suitably mounted for lengthwise punching movement and are urged toward and normally held in retracted position by tension springs 15. Punch actuating levers 20 to 26 inclusive are operatively connected, respectively, to the feed hole punch FP and the code punches RP1 to RP6, inclusive, and the actuating levers 20 to 26 inclusive are supported, respectively, intermediate their ends by eccentric portions 27 fixed to a rotatably mounted vertical operating shaft 28. The shaft 28 is connected at its upper end by suitable gearing 29 to a horizontal operating shaft 30. Seven latch levers 40 to 46 inclusive are provided, respectively, for the seven punch actuating levers 20 to 26 inclusive. Each latch lever, when tripped in a manner which will be presently explained, engages and holds against movement the end of its related punch actuating lever which is remote from its code punch. With an actuating lever so held by its related latch lever and upon the shaft 28 being rotated, the eccentric portion 27 will move such actuating lever about the end thereof which is held by its related latch lever and will thereby move its related code punch lengthwise into punching engagement with the record sheet.

As a feed hole 13 is punched in the tape by the

punch FP during each operation of the apparatus, the latch lever 40 corresponding thereto is always in tripped position and thereby holds the adjacent end of its punch actuating lever 20 against a stationary stop bar 41. Fig. 1 shows the latch lever 40 in tripped position. The other latch levers 41 to 46 corresponding, respectively, to the six code punches RP1 to RP6 inclusive, are normally held out of untripped or latched position, by armatures 48 of related selector magnets. There are six selector magnets RM1 to RM6, inclusive (see also Fig. 2), and they coat, respectively, with the six latch levers 41 to 46 inclusive to control the operation of the latter and the operation of their related code punches. If a latch lever is held in its normal or untripped position when the shaft 28 is rotated, the spring 15 of its related code punch is strong enough to hold the latter in its retracted position and thereby also hold the adjacent end of its related punch actuating lever. Thus when the shaft 28 is rotated, each punch actuating lever which is not latched by its related latch lever will move about the end thereof which is connected to its related code punch and the end of the punch actuating lever which is remote from its code punch will move outward and away from the stop bar 41.

The selector magnets RM1 to RM6 inclusive are selectively energized in a manner which will be presently explained and, when energized, attract their related armature 48 and thereby release, or trip, their related latch levers. A tension spring 50 is attached to each of the latch levers, and when each of the latch levers 41 to 46 inclusive is released by the energizing of its related selector magnet, its spring 50 moves such latch lever about a fulcrum support shaft 51 and into latching engagement with the end of its related punch actuating lever.

As explained in my copending application referred to above, the code tape punch 10 is cyclically operable under the control of a clutch magnet CLM. A main drive shaft 53 is continuously rotated by a pulley 54 and belt 55 from a suitable electric motor, not shown in Fig. 1 but indicated diagrammatically in Fig. 2 by the reference character 56. A one-revolution clutch 57 is provided and functions each time it is tripped by the energizing of the clutch magnet CLM to connect the punch operating shaft 30 to the drive shaft 53 so that the operating shaft 30 (and shaft 28) is rotated for one revolution and then disconnected from the drive shaft 53.

The construction and operation of the one-revolution clutch 57 is shown and described in detail in my copending application, referred to above, and consequently a full disclosure thereof is not necessary herein, it being sufficient to say that each time the clutch magnet CLM is energized its armature 58 is attracted against the force of a tension spring 59 so that the end 60 thereof moves out of engagement with a projecting element 61 of the clutch 57 and the latter moves under the force of a spring (not shown) to effect engagement of a sliding dog 62 with a ratchet wheel 63. The dog 62 is mounted in a clutch barrel 64 fixed to the shaft 30 and the wheel 63 is fixed to the drive shaft 53, so that their engagement provides a driving connection between the shafts 53 and 39. As will appear hereinafter, the magnet CLM is deenergized as soon as the shaft 30 commences rotating, and the spring 59 will then move the end 60 of the armature 58 into engagement with the barrel 64 so that it will lie within the path of movement

of the projecting element 61 of the clutch. When the latter engages the end 60, the clutch 57 is thereby disengaged and the shaft 30 is held in the disengaged or declutched position shown in Fig. 1.

As shown in Fig. 1, a bail member 66 is rotatably mounted on the fulcrum shaft 51 and extends across all of the latch levers 40 to 46 inclusive. The lower end of the bail member is formed with a rearwardly extending arm 67 and the outer end of the latter coacts with the movable spring blade 68 of a pair of contacts 69. The arrangement is such that when any of the selector magnets RP1 to RP6 inclusive is energized and its related latch lever is released such latch lever will engage the bail 66 and move the latter against the spring force of the blade 68 to close the contacts 69. As disclosed in my copending application referred to above, the latch lever 40 for operating the feed punch FP is notched out so that it will have no effect on the operation of the bail member 66. As will be apparent hereinafter when the wiring diagram shown in Fig. 2 is described, the bail contacts 69 are connected in series with the coil of the clutch magnet CLM and with a pair of contacts 70 operated by a cam 71 on the punch operating shaft 30. When in home position, the cam 71 holds the contacts 70 closed. Thus, when the pair of bail contacts 69 are closed as a result of the energizing of a selector magnet, as just explained, the clutch magnet CLM is energized to operate the clutch 57 and a cycle of rotation of the operating shafts 30 and 28 is effected. Soon after the beginning of a cycle of rotation, a cam 73 on the lower end of shaft 28 moves a follower arm 74 and locking bail 75 against the force of a tension spring 76 and into engagement with the latch levers 40 to 46 inclusive. The construction is such that when so moved, the locking bail 75 will function to lock or hold any latch levers which have been tripped in their latched position and will hold any latch levers which have not been tripped in their untripped position. The locking bail 75 remains in operative engagement with the latch levers until after the code holes are punched. After the punching of the code holes, a knock-off bail 78 fixed to the fulcrum shaft 51 and operated through an arm 79, also fixed to the shaft 51, from a pin 80 projecting from one side of the cam 73, engages all of the latch levers which have been previously tripped and moves the latter out of latching engagement with their punch acting levers and back to their untripped position. Concurrently with the latter, a pair of armature knock-off bails 82 and 83, operated, respectively, by arms 84 and 85 from eccentric pins 86 and 87 projecting from opposite sides of a disk 88 fixed to the shaft 28, move into engagement with the armatures 48 of the selector magnets and move the armatures outward from their coils so that when the latch levers are moved by the knock-off bail 78, as just explained, the ends 90 of such latch levers are engaged and latched again by their related armatures. A full disclosure of the detailed construction and operation of these bails during a cycle of operation of the apparatus is included in my copending application and consequently further detailed description herein is considered unnecessary.

During the latter part of the cycle of operation of the operating shaft 30 and 28 a cam 92 fixed to the shaft 28, engages a follower 93 and through a connecting pin 94 moves a dog 95 into engagement with a ratchet wheel 96 fixed to the tape feed shaft 97 and thereby advances the tape to

move the next blank recording field into recording position.

As disclosed in my copending application, referred to above, the operation of the tape punch 10 may be controlled by the conventional key actuation of a typewriter (not shown herein). As the control by the typewriter is not a part of the present invention it is believed sufficient for the purposes of the present disclosure to say that each time a typewriter key is depressed, a permutation unit (not shown) selectively closes code contacts corresponding to the code designation of the typewriter key actuated and such code contacts close energizing circuits for corresponding selector magnets of the group RM1 to RM6 and thereby effect a cycle of operation of the recording apparatus, during which a code designation representing the key actuated is recorded in the tape 11 and the tape is then spaced, as was described previously. In Fig. 2 of the drawings, the code contacts selectively closed by the permutation unit as a result of the just explained typewriter key actuation, are shown and are indicated by the reference characters SC1 to SC6 inclusive, and they are connected, respectively, by six code wires 111 to 116 inclusive to the six code selector magnets RM1 to RM6 inclusive. As explained in said copending application, the operation of the typewriter keys and the permutation unit is such that the code contacts are selectively closed momentarily and while closed common contacts C are closed to complete an energizing circuit for the selector magnets.

The electrical circuits to effect the just described operation of the tape punch will now be described. The wires 100 and 101 are adapted to be connected to the available alternating current supply, such as a 110 volt A. C. line. Two power switches are provided and are indicated at 103 and 104. The switch 104 is mounted on the typewriter (not shown) and when closed establishes an energizing circuit through a motor 105 which, as explained in my copending application referred to, actuates the typewriter. One side of the motor is connected to the A. C. supply wire 100 and the other side of the motor is connected by a wire 106 and the power switch 104 with the other A. C. supply wire 101. The power switch 104 when closed also connects the A. C. supply wire 101 with a wire 107 which is in turn connected to a contact 120 of the power switch 103. The latter is a double pole single throw switch and, when closed, one blade 121 thereof engages the contact 120 to connect the punch motor 56 across the A. C. line and to supply A. C. to the primary 122 of a transformer 123. The latter circuit extends from the closed blade 121, which as just stated is connected through the closed switch 104 to the A. C. wire 101, through the wire 124, the motor 56 and primary 122 in parallel, a wire 126, and to the other A. C. supply wire 100. Thus with the switches 104 and 103 both closed, the motors 105 and 56 will operate continuously and current is supplied to the primary 122 of the transformer 123.

The secondary 127 of the transformer is connected across the input terminals of a conventional form of full wave rectifier 128. The latter supplies direct current for the control circuits of the recording apparatus. The positive output terminal of the rectifier is connected to the positive D. C. supply wire 130 and the negative output terminal is connected to the negative supply wire 131. The negative wire 131 is connected through the other blade 132 of the power switch

103 with a wire 133 which, as shown, is connected to the return side of the clutch magnet CLM and to the return sides of each of the selector magnets RM1 to RM6 inclusive. The positive wire 130 is connected to the upper contact of the pair of common contacts C.

A cycle of operation as controlled by the code contacts SC1 to SC6 inclusive will now be described. As explained in my copending application referred to above, when a typewriter key is actuated one or more pairs of code contacts of the group SC1 to SC6 inclusive which correspond to the code designation of such key, are closed. Shortly thereafter the common contacts C are closed and a circuit is established from the D. C. positive wire 130 through the common contacts C, the pair of code contacts, or pairs of code contacts, of the group SC1 to SC6 inclusive which have been closed by the actuation of the typewriter key, the corresponding code wire, or wires, of the group 111 to 116 inclusive, the corresponding selector magnet, or magnets, of the group RM1 to RM6 inclusive, the wire 133, the switch blade 132 to the negative DC wire 131. As explained above, the energization of the selector magnets will result in the closing of the bail contacts 69 and in establishing an energizing circuit for the clutch magnet CLM which is traced as follows: from the positive wire 130, bail contacts 69 now closed, wire 135, cam contacts 70 which are closed at the home or inactive position of the tape punch, the clutch magnet CLM and the wire 133 to the negative wire 131. The energization of the clutch magnet will provide for one revolution of the shafts 28 and 30, during which the code designation corresponding to the typewriter key actuated is punched in the tape. The tape is advanced by the feed wheel 12 and the code tape punch is restored to its home or inactive position shown in Fig. 1.

In accordance with the present invention a new and improved means is provided which contacts with the elements of the punching apparatus to control the operation of the latter. This operation control means functions in response to the actuation of a manually operated key to effect one cycle of operation of the punching apparatus to record in the tape a particular code designation selected for such key. This operating control means also functions to prevent a second operation of the punching apparatus until such key is first released and then actuated a second time.

In Fig. 2 two manually operated keys 140 and 141 are provided for actuating the just mentioned operating control means to effect the recording of the selected code designation, these keys corresponding, respectively, to the keys 104 and 204 in my copending application referred to above, and, as explained in such application, the reason for providing two such keys is solely for convenience. The key 140 is located on the tape punch 10. As in the copending application, the depressing of either key 140 or 141 effects the recording of a "Stop" code designation, which is a code hole in code positions 1, 4, 5 and 6.

As the depressing of either key 140 or key 141 provides for the same operation, such operation will be described in connection with only the key 141. As shown in Fig. 2, the code wires 111, 114, 115, and 116 are connected, respectively, to normally open key contacts 144, 145, 146, and 147, and a normally open key contact 148 is con-

nected by a wire 149, wire 150, normally closed relay contacts 151, and wire 152 with the positive D. C. supply wire 130. When the key 141 is depressed the contacts 144, 145, 146, and 147 are all connected to the contacts 148 and a code punch selecting circuit is thus establishing which is traced as follows: from the positive wire 130, through the wire 152, normally closed relay contacts 151, wire 150, wire 149, contacts 148, 147, 146, 145, and 144, the code wires 111, 114, 115, and 116 in parallel, the code selector magnets RM1, RM4, RM5, and RM6 in parallel, the wire 133, and switch blade 132 to the negative wire 131. Thus, when the key 141 is depressed the selector magnets RM1, RM4, RM5, and RM6 are energized, the bail contacts 69 are closed to energize the clutch magnet CLM and a cycle of operation of the punching apparatus is effected, during which code holes are punched in the positions 1, 4, 5, and 6 of the tape which represent the "Stop" code. It will be appreciated that any other code designation could be selected if desired.

In order to prevent repeat operations of the punching apparatus when the key 141 is depressed in the manner just described, a non-repeat relay 160 is provided which includes a coil 161, the pair of normally closed contacts 151, referred to above, and a pair of normally open hold contacts 162. The key 141 is also provided with a pair of normally open contacts 163 which are insulated from its other contacts 144, 145, 146, 147, and 148, but are closed along with the latter when the key is depressed. One contact of the pair 163 is connected by a wire 164 with the positive supply wire 130 and the other contact of the pair 163 is connected by a wire 165 and wire 166 to one of the pair of normally open cam operated contacts 8, and the other of the pair of cam contacts 8 is connected by a wire 167 with one side of the relay coil 161, the other side of the latter being connected by a wire 168 with the negative terminal of the rectifier 128. As shown in Fig. 1, the cam 7 is mounted on the punch operating shaft 30 and the contacts 8 operated thereby are open at the home or inactive position of the shaft. The normally open pair of relay hold contacts 162 are connected, respectively, with the wire 166 and wire 167 so that when the hold contacts close, they shunt out the cam contacts 8.

From the foregoing, the operation which takes place as a result of depressing the key 141 will be apparent. In addition to closing the code punch selecting circuit and thereby effecting operation of the punching apparatus, as previously described, the key 141 when depressed also closes the contacts 163 and thereby conditions an energizing circuit for the non-repeat relay 160. The circuit thus conditioned, is completed when the cam 7 on the punch operating shaft 30 closes its contacts 8. The relay 160 when thus energized opens its normally closed contacts 151 to break the punch selecting circuit previously traced, and closes its hold contacts 162 to shunt the cam con-

tacts 8 and thereby hold the relay 160 energized as long as the key 141 is held depressed to close the contacts 163. Thus, the punch selecting circuit cannot be reestablished until the key 141 is released to open the relay hold contacts 162 and drop out the non-repeat relay 160 and thereby permit its contacts 151 to again close.

It will be readily understood by those skilled in this art that while the operation control means has been disclosed herein as providing for the recording of only one selected code designation when either of two keys is depressed, it may be readily modified so that the two keys 140 and 141 will effect the recording of different codes. For example, the normally open contacts 144a, 145a, 146a, and 147a of the key 140 may be simply connected to selected code wires other than those shown. In the same manner any additional number of keys may be provided to record different code designations selected therefor.

While there have been shown and described and pointed out the fundamental novel features of the invention, as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claim.

What is claimed is:

In recording apparatus comprising an operating shaft, a source of power, a clutch magnet operable when energized to connect said power source and said shaft for rotating the latter for one operating cycle, a plurality of code punches corresponding, respectively, to the code positions of a preselected code system and being operatively connectable to said shaft, when selected, to punch code holes in corresponding code positions in a record sheet, a plurality of selector magnets corresponding, respectively, to said code punches and operable when energized to select their related punches, and means operable, when a selector magnet is energized, to energize said clutch magnet; the combination of a non-repeat electrical relay including a pair of normally-open hold contacts, and a pair of normally-closed contacts; a code punch selecting circuit including a source of electrical energy, a predetermined number of said selector magnets, said pair of normally-closed relay contacts, and a plurality of normally-open key contacts operable when closed to connect said predetermined number of selector magnets across said energy source through said normally-closed relay contacts; an energizing circuit for said relay including in series, the coil of said relay, a pair of normally-open key operated contacts, and a pair of normally-open cam contacts closed by the punch shaft during a cycle of operation, the hold contacts of said relay being connected in shunt across said cam contacts; and a manually operable key device for closing simultaneously all of said key contacts.

HENRY L. THOLSTRUP.
